F. P. SHARP.

RATCHET DRILL.

APPLICATION FILED NOV. 6, 1916.

Patented Feb. 5, 1918.

UNITED STATES PATENT OFFICE.

FRANK P. SHARP, OF OAKLAND, CALIFORNIA.

RATCHET-DRILL.

1,255,803.

Specification of Letters Patent. Patented Feb. 5, 1918.

Application filed November 6, 1916. Serial No. 129,867.

To all whom it may concern:

Be it known that I, FRANK P. SHARP, a citizen of the United States, residing at Oakland, in the county of Alameda, State of California, have invented a new and useful Ratchet-Drill, of which the following is a specification in such full and clear terms as will enable those skilled in the art to construct and use the same.

10 This invention relates to a ratchet drill, an object of which is to produce a drill capable of being turned in a very short space by reason of the fact that the ratchet holds by friction and thereby enables the drill to be turned with very short strokes.

Another object of the invention is to produce a handle for a drill capable of having either the drill head inserted or a socket wrench holding head inserted therein at the will of the operator.

20 Another object of the invention is to provide the drill feed screw cap with a friction guide rod which will hold the feed screw cap in any given adjustment while the drill is being used, and which will support it more rigidly when partly extended.

Another object of the invention is to provide an oscillating cam or pawl which will frictionally engage to the wrench or drill head, and which may be easily assembled when it is desired to change from the socket wrench to the drill head.

30 Another object of the invention is to provide the revoluble head which carries the drill or wrench with a series of shallow flutes which will insure the proper frictional engagement of the cam and revoluble head while at the same time making it possible to turn the head with exceedingly short strokes, each flute being only about one sixteenth of an inch wide and about one sixty-fourth of an inch deep, and the flutes are spaced apart so as to provide a bearing for the head in the recess in which it is placed.

40 An embodiment of the invention is shown in the drawing in which the same reference numeral is applied to the same portion throughout, but I am aware that there may be many modifications thereof within the scope of the appended claims.

Figure 1 shows a side elevation of the drill with a portion of the handle broken away for the purpose of illustration.

50 Fig. 2 is a side elevation of the handle of the drill, the drill head and operating end

of the handle being shown in vertical section.

Fig. 3 is a plan view of the operating end of the handle with the drill head retaining plate broken for the purpose of illustration.

Fig. 4 is a bottom plan view of the drill head and handle as shown in Fig. 1, and

Fig. 5 is a vertical sectional view of the socket wrench operating head.

The drill consists of a handle 1 with an 65 enlarged operating head 2. The head 2 is bored to receive the drill head 3, a plate 4 with a plurality of screws 5 holding the drill head in place in the head 2 of the handle. The outside of the drill head is cylindrical 70 and in a pocket 6 of the head 2 there is an oscillating or pivoted cam 7, said cam being so shaped as to allow the head 3 to slip when the cam is moved in one direction, while it will carry the head 3 along with it 75 when it is moved in the opposite direction. The cam or pawl has an arm 8 upon which bears a spiral spring 9 which holds the cam in engagement with the flutes 3' on the outside of the head 3. In order to feed the 80 drill the head 3 is provided with a threaded shank 10 over which a knurled sleeve 11 is screwed. The spring 9 has a straight portion which extends into a hole in the cam to hold it while the cam is being assembled. 85

The knurled sleeve 11 is screwed on a short stud 12 of the cap 13 which forms the bearing for the end of the shank. The stud 12 has integrally therewith a rod 14 which is split at 15 so that it will bear tightly on 90 the inside of the shank 10, the object being to hold the shank 10 and sleeve 11 in a given adjustment when set by the user. In order to prevent the sleeve 11 from screwing off of the short stud 12, a pin 16 is driven 95 through a hole in the stud, one half of said pin being seated in a notch in the upper end of the sleeve 11. The drill head has an opening 18 in its underside to receive the shank of the drill to be used therewith. 100

When it is not desired to use the drill but is wanted as a socket wrench the head shown at 22 is substituted for the head 3 in the handle, the plate 4 being removed to take out the drill chuck after which the socket 105 22 can be inserted. This head has a flange 21 upon which the cam 7 bears the same as it does upon the outside of the head 3.

The operation of the drill is as follows:—

Assuming a drill bit to be placed in the 110

opening 18, the sleeve 11 is screwed out against some fixed object, its upper end bearing upon the same and the drill is rotated with short or long strokes of the handle 1, and as the drill goes into the material, the sleeve 11 is rotated by hand or by inserting a rod in one of the holes 23, 24, in its upper end until the drill again bears tightly upon the material being cut and the same proceeding is continued until the hole is completed.

Having thus described my invention what I claim as new and desire to secure by Letters Patent of the United States, is as follows:—

1. A device of the character described having an enlarged head, a revoluble drill holding head therein having a hollow threaded shank, a threaded sleeve on said hollow shank, said sleeve having a steadyng rod

split at one end and bearing frictionally upon the inside of the hollow threaded shank.

2. A device of the character described comprising the combination of a handle 25 with an enlarged head, having a cylindrical seat therein, a revoluble head in contact with said seat and having a plurality of shallow separated flutes, a pivoted cam in the handle head, the face of which contacts 30 with and is of substantially the same curve as said flutes on the fluted head, a flat arm carried by the cam and a spiral spring supported by the cam and bearing on the flat arm to hold the fluted head.

In testimony whereof I have hereunto set my hand this 27th day of October A. D., 1916.

FRANK P. SHARP.
